UNITED STATES PATENT OFFICE.

LOUIS B. SMITH, OF JAMESTOWN, NEW YORK.

FLUSHING-VALVE.

SPECIFICATION forming part of Letters Patent No. 718,225, dated January 13, 1903.

Application filed August 1, 1901. Serial No. 70,539. (No model.)

To all whom it may concern:

Be it known that I, LOUIS B. SMITH, a citizen of the United States, residing at Jamestown, in the county of Chautauqua and State 5 of New York, have invented a new and useful Flushing-Valve, of which the following is a specification.

This invention relates to flushing-valves, and has for its object to provide an improved 10 water-closet valve for controlling the supply of water to the closet-bowl, so as to give the latter a sudden powerful flush of water for cleansing the same and also to facilitate the manipulation of the valve and to insure a 15 quick and effective operation thereof. It is, furthermore, designed to arrange for an after-flush when the main flush has ceased and immediately prior to the complete shutting off of the water.

20 With these and other objects in view the present invention consists in the combination and arrangement of parts, as will be hereinafter more fully described, shown in the accompanying drawings, and particularly 25 pointed out in the appended claims, it being understood that changes in the form, proportion, size, and minor details may be made within the scope of the claims without departing from the spirit or sacrificing any of 30 the advantages of the invention.

In the drawings, Figure 1 is a longitudinal sectional view of a flushing-valve constructed in accordance with the present invention. Fig. 2 is an enlarged detail sectional view 35 taken through the controlling-valve proper, showing the position of the parts when the valve is closed. Fig. 3 is a similar view illustrating the movement of the valve during the flush. Fig. 4 is a detail side elevation of the 40 controlling-valve. Fig. 5 is a detail elevation of the water-flow regulator.

Like characters of reference designate corresponding parts in all of the figures of the drawings.

45 Referring at first to Fig. 1 of the drawings, it will be seen that the valve-casing is formed in upper and lower tubular sections 1 and 2, of which the lower section is slightly greater in diameter and has its lower end reduced 50 and internally screw-threaded to form a coupling 3 for connection with the water-main to receive the supply of water. The lower edge

of the upper section is provided with an outwardly-offset cylindrical flange 4, which rests upon the top edge of the lower section, to 55 which it is connected by an internally-screw-threaded coupling or collar 5, whereby the sections are detachably connected. Within the lower section there is provided an internal tubular open-ended shell or chamber 6, 60 which has its upper end snugly embraced by an inner marginal flange 7 at the upper end of the lower casing-section, while the lower end of the shell is supported upon and closed by a bottom plate 8, which has a pendent central standard or stem 9, that is supported centrally in a spider 10, formed integrally with the lower end portion of the lower casing-section. To provide a water communication between the lower portion of the casing and the 70 lower end of the internal chamber, a transverse inlet-opening 11 is formed through the supporting-standard 9 and adjacent to the plate 8, there also being a vertical port 12 formed through the plate and extending downwardly adjacent to one side of the inlet-opening and in communication therewith by means of a short transverse passage. For controlling this port there is provided a needle-valve 13, piercing one side of the lower casing-section, 80 passing transversely through the inlet-opening 10, and entering the side of the port to close the same through the passage between the inlet-opening and port. This valve is accessible from the exterior of the casing to control 85 the supply of water to the inner chamber. It will be understood that the water also rises between the casing and the chamber and has access to the interior of the latter through perforations 14, formed around the upper portion 90 of the shell.

At the upper end of the lower casing-section there is provided a valve-seat consisting of an open-ended tube 15, lying wholly in the upper casing-section and provided at its lower 95 end with an outwardly-directed marginal flange 17, forming the seat proper and having an outer cylindrical rim 18, which embraces the upper end of the shell 6 and is clamped between the cylindrical flange 4 of the upper casing-section and the inner marginal flange 7 of the lower section, whereby all of these parts are snugly and detachably connected. Upon the upper end of the tube

15 there is mounted a cap 19, constituting a regulator for controlling the column of water that passes through the valve, the regulator having perforations or openings 19' for the 5 escape of water and is adjustably connected to the tube by a screw-threaded connection. It will be observed by reference to Figs. 1 and 2 that the seat 15 is of a height equal to that portion of the controlling-valve 20 within the 10 seat, or it may be a little higher, so that when the regulator is screwed down upon the seat 15 to its lowest point, or, in other words, until the under face of the regulator abuts against the seat, there will be no interference 15 between it and the valve 20; otherwise the valve could not seat itself, and thus cut off passage of water through the valve. The function of the regulator is to control the volume of flow of water through the valve in 20 accordance with the pressure of the main. Thus if the main-pressure be very high the usual one-inch head would be too much, as it would result in the water splashing out of the bowl, and under these conditions the regulator 25 would be turned down partly to close the openings 19'. If, on the other hand, the main-pressure be low, the said openings can be left open to their fullest extent. By this simple yet effective element a serious objection 30 common to valves of this character is effectively obviated.

The controlling-valve 20 normally closes the seat 15 and consists of a solid metallic cylinder which has a central longitudinal bore 35 or passage 21 and a lower reduced stem portion 22, thereby forming a marginal shoulder 23 at the inner end of the stem portion. The intermediate portion of the valve is provided with an external marginal beveled groove 40 24 for a purpose as will be hereinafter described. Within the upper end of the bore of the valve there is removably fitted a tubular stem 25, which is slidably projected through a central opening in the top of the cap or regulator 19, which forms a guide therefor. Upon the lower stem portion of the valve there is provided a rubber or other suitable gasket 26, which is of greater diameter than the valve and is designed to be held 45 up against the valve-seat to close the same, as shown in Fig. 1. The gasket is held snugly against the shoulder 23 by means of a nut 27, screwed upon the pendent stem portion, and a fluid-actuated valve-operating piston 50 28, fitting snugly the shell or piston-cylinder 6, is held upon said stem portion and against the nut 27 by means of the tubular valve-casing 29, also screwed upon the stem. The lower end of the stem portion 22 is bevelled inwardly to form a valve-seat 30, and screwed to the exterior of this end portion is the tubular valve-casing, which is provided with a marginal series of perforations 32 adjacent to its upper end and just below the 55 valve-seat, the lower end of the casing being open for the slidable reception of the stem 33 of a relief-valve 34, that is normally seated

by means of the water-pressure within the shell or inner chamber 6 and designed to be unseated by means of a push-rod 35, slidably 70 mounted within the tubular portion of the valve and projected upwardly through the top of the casing for convenient access.

That portion of the push-rod which projects above the top of the casing is housed 75 within a tubular casing 36, through the top of which the rod projects, and is provided with a handle 37, having an internally-screw-threaded stem 38, receiving the screw-threaded upper end of the rod and working 80 slidably in the casing, there being a helical spring 39 embracing the rod and bearing in opposite directions against the bottom of the rod-casing and the stem to normally hold the rod in an elastically-yieldable elevated position with its lower end above and out of contact with the relief-valve, as clearly illustrated in Fig. 2 of the drawings. Upon examination of Fig. 1 it will be seen that the internal bottom portion of the casing 36 is 85 beveled inwardly and downwardly to the opening thereof, as at 40, thereby forming a substantially conical seat for the reception of the packing 41. The lower end of the helical spring bears directly upon this packing, 95 so that when the rod is depressed the spring exerts a downward pressure upon the packing, which is drawn snugly inwardly against the rod to form a water-tight joint by reason of the beveled seat 40. A suitable stop 42 is 100 carried by the rod and arranged to engage the top of the valve-casing, thereby to form a stop to limit the upward or outward movement of the rod. The stop 42 in engaging with the top of the valve-casing will serve to 105 prevent the escape of water through the stuffing-box, and in order to insure a waterproof joint it may carry a washer of leather or other yielding material on its upper surface.

A lateral discharge-pipe 43 connects with 110 the upper portion of the valve-casing and above the valve to carry off the water to the bowl of the closet. (Not shown.)

For an explanation of the operation of the device reference is first had to Fig. 1, where-in it will be observed that the valve portion 26 is seated to close the passage between the lower and upper parts of the valve-casing, the valve being held by the pressure of the water entering the lower end of the casing from the main and passing upwardly within the inner shell 6 and also upwardly upon the exterior of the shell and inwardly through the perforations 14, whereby an equal pressure is maintained upon opposite sides of the piston 28, 115 thus holding the latter fixed and the valve closed. Furthermore, the water within the inner shell or chamber passes into the valve-casing 29 through the perforations thereof and seats the relief-valve 34, thus effectually 120 shutting off communication between the upper and lower parts of the casing. When it is desired to produce a sudden and violent flush of water, the push-rod 35 is depressed 125 130

by pressing upon the handle thereof until its lower end unseats the relief-valve 34, thereby relieving the pressure in the inner chamber 6 and permitting of the water therein passing into the valve-casing 29 and thence upwardly through the bore and tubular stem portion of the valve and into the upper section of the valve-casing proper. Immediately upon the relief of the pressure in the inner chamber 5 the normal pressure upon the upper side of the plunger forces the latter downwardly, thereby unseating the gasket part 26 and permitting the water to pass upwardly through the tubular seat portion 15, as is apparent by 10 reference to Fig. 3. As the water rushes into the upper casing portion it also discharges outwardly through the pipe 43 to the closet in a quick violent stream. The plunger and valve continue to move downwardly until the projected end of the relief-valve stem strikes the bottom of the inner chamber, which forms a 15 trip to automatically close the said relief-valve, and when the latter has been closed the water in the chamber cannot escape, 20 whereby the pressure is greater upon the under side of the plunger and the latter is forced to rise until the gasket portion 26 again closes and automatically stops the flush.

It will be understood that the cylindrical 30 valve portion 20 fits loosely within the tubular seat portion 15, so as to permit of the upward flow of water between the valve and seat immediately upon the unseating of the valve, the full flush, however, not coming until after the valve has dropped entirely out 35 of the seat. The greater portion of the flush is stopped when the valve portion 20 first enters the seat, and as the opening at the seat portion is slightly less in diameter than the 40 main body of the portion 15, owing to the presence of an inwardly-projecting marginal flange at this point, the marginal groove 24 of the valve 20 when registered with the opening of the valve-seat will form an enlarged 45 annular passage and produce an afterflush in advance of the final closing of the valve.

What is claimed is—

1. In a flushing apparatus, the combination with a casing having an inlet and an outlet, 50 a valve-seat located between the inlet and the outlet, an open-ended piston-cylinder fitted to the seat and terminated short of the inlet, a spider within the casing and adjacent to the inlet, a standard rising from the spider 55 and having an upper terminal enlargement fitted to the bottom of the cylinder to close and support the same, there being a valve-controlled inlet-port in the bottom of the cylinder, and an inlet at the upper end thereof, 60 a controlling-valve for the seat and working within the cylinder, a fluid-operated valve-actuating piston working in the cylinder, a relief-valve carried by the piston, and means for controlling the relief-valve, the piston being located between the opposite inlets of the cylinder.

2. The combination in a flushing apparatus,

of a valve-casing having a contracted mouth and forming an end valve-seat, an elongated cylindrical valve-body adapted to enter said casing and provided with a radially-enlarged portion adapted to close against said seat, the intermediate portion of said valve-body being provided with a marginal groove considerably in advance of the seating portion and having a tapering or inclined wall, whereby on the closing movement, the flow of water will be almost entirely checked by the entrance of the valve-body within the casing, the further movement of the valve-body permitting of an afterflush, and thereafter during the remaining movement the flow being gradually diminished by the reduction in the area of the annular passage between the valve-seat and the inclined wall of said marginal groove, substantially as specified. 75

3. In a flushing apparatus, the combination with a valve-seat, of an elongated valve-body working loosely through the seat, and provided with a terminal marginal enlargement 90 for coöperation with the seat to close the same and located at the rear end of the body with respect to the direction of the closing movement thereof, there being an intermediate marginal groove formed about the body and 95 constructed to coöperate with the reduced seat-opening and form an afterflush, the valve-body serving to check the afterflush and permit the passage of but a small quantity of water until the final closing of the 100 valve.

4. In a flushing apparatus, a valve consisting of an elongated body adapted to partially close the opening of the valve-seat with which it coöperates, and said valve having an intermediate marginal groove and terminal marginal enlargement. 105

5. In a flushing apparatus, a valve consisting of an elongated body adapted to partially close the opening of the valve-seat with which it coöperates, said body portion having at a point intermediate of its length a marginal groove having its walls inclined in opposite directions, and being provided with a radially-enlarged portion forming a closure for the 110 valve-opening, said marginal groove being arranged considerably in advance of the radially-enlarged portion and serving to check the flow of water before the final seating of the valve, substantially as specified. 120

6. In a flushing apparatus, a valve consisting of an elongated valve-body having a central bore terminating in a tubular stem, and also provided with an intermediate marginal external groove, a gasket fitted to the 125 stem and against the adjacent end of the valve and of greater diameter than the latter, a nut applied to the stem and against the gasket, a piston applied to the stem and against the nut, a tubular valve-casing fitted to the outer end of the stem and against the piston, there being perforations in the casing, and a relief check-valve within the casing and having a projected stem. 130

7. In a valve, the combination with a seat having an open-ended tubular portion projected from the port thereof and provided with external screw-threads, of a fluid-actuated valve having a portion working through the valve - seat and projected upwardly through the tubular portion and a terminal enlarged portion to close against the seat, and a cap having perforations in its head and flange portion, said flange portion having internal screw-threads adapted to the threads on the upper end of the tubular portion, and a tubular valve-stem secured to said valve and adapted to a guiding-opening formed in the cap, substantially as specified.

8. In a flushing apparatus, the combination with a casing having an inlet and an outlet, of a valve-seat located intermediate thereof and provided with a tubular portion projected toward the outlet, a piston-cylinder projected from the seat and opposite the tubular portion thereof, there being inlets at opposite

ends of the cylinder, a hollow cylindrical valve working through the seat and projecting through the tubular portion thereof, there being an enlarged portion at one end of the valve to close against the seat, tubular stems projected at opposite ends of the valve, a piston fitted to one of the stems and working in the piston-cylinder between the opposite inlets thereof, a relief-valve for the said stem, a perforated cap adjustably connected to the upper end of the tubular valve portion and having a central opening for the adjacent valve-stem, and a push-rod projected through the latter stem and in operative relation to the relief-valve for unseating the same.

In testimony that I claim the foregoing as my own I have hereto affixed my signature in the presence of two witnesses.

LOUIS B. SMITH.
